MERCHANDISE DISPLAY CHANGE RECEPTACLE

Filed Dec. 8, 1934

Inventor:

Peter Rhode
By Dyerforth, Lee, Gritten & Wils,
Attn: S.

UNITED STATES PATENT OFFICE

95,148

DESIGN FOR A MERCHANTISE DISPLAY CHANGE RECEPTACLE

Peter Rhode, Kenosha, Wis.

Application December 8, 1934, Serial No. 54,365

Term of patent 7 years

To all whom it may concern:

Be it known that I, Peter Rhode, a citizen of the United States of America, residing in Kenosha, in the county of Kenosha and State of Wisconsin, have invented a new, original, and ornamental Design for a Merchandise Display Change Receptacle, of which the following is a specification, reference being had to the accompanying drawing, forming a part thereof, in which—

The figure is a perspective view of a merchandise display change receptacle showing my new design.

I claim:

The ornamental design for a merchandise display change receptacle substantially as shown.

PETER RHODE.
